DISHWASHING MACHINE

George Webb, West Hartford, Conn., assignor to
 Colt's Patent Fire Arms Manufacturing Co.,
 Hartford, Conn., a corporation of Connecticut

Application July 29, 1932, Serial No. 625,668

4 Claims. (Cl. 141—9)

The invention relates particularly to dish washing machines of the type wherein each machine comprises a casing in which the dishes are subjected to jets of washing liquid forcibly directed against them. The jets are ordinarily oppositely directed to act on the dishes at opposite sides thereof. While the invention is, in the main, particularly applicable to machines of the class mentioned it is not necessarily so limited as to all of its features.

When there are two sets of jet devices above and below the path or position of the dishes, these oppositely directed jets oppose each other and a considerable amount of splash and spray is formed as the result of their impact. A dish washing machine ordinarily has doors or curtains for the purpose of confining this splash or spray to the interior of the casing; but a considerable quantity escapes if the doors are opened or if the curtains are lifted while the jet devices are in action. One of the objects of the present invention is to provide a liquid curtain or an additional jet device which serves to reduce to the minimum the escape of splash or spray even when the opening to the interior of the casing is otherwise unprotected.

Another object of the invention is to provide, either in association with the protective liquid curtain or otherwise, splash guards and flexible curtains of novel design and arrangement which still further reduce the amount of splash or spray escaping through the opening in the casing.

Other objects of the invention will be apparent from the following specification and claims.

I do not herein specifically claim the jet device which is disclosed, this being made the subject of my patent for Jet device for dishwashing machines, No. 1,966,573 issued July 17, 1934 upon an application filed as a division of this present application.

In the accompanying drawings I have shown one embodiment of the invention, but it will be understood that the drawings are intended for illustrative purposes only and are not to be construed as defining or limiting the scope of the invention, the claims forming a part of this specification being relied upon for that purpose.

Of the drawings:

Fig. 1 is a side view of a dish washing machine embodying the invention, certain parts of the machine being shown in section along the line 1—1 of Fig. 3.

Fig. 2 is a right end view of the machine with certain parts shown in section along the line 2—2 of Fig. 1.

Fig. 3 is a horizontal sectional view taken along the line 3—3 of Fig. 1.

Fig. 4 is a horizontal sectional view taken along the line 4—4 of Fig. 1.

Fig. 5 is a transverse sectional view taken along the line 5—5 of Figs. 1 and 3.

Fig. 6 is a fragmentary sectional view taken along the line 6—6 of Fig. 1.

Fig. 7 is an enlarged fragmentary sectional view taken along the line 7—7 of Fig. 1.

Fig. 8 is a fragmentary sectional view of the suction guard, this view being taken along the line 8—8 of Fig. 4.

Fig. 9 is a fragmentary sectional view taken along the line 9—9 of Fig. 8.

Fig. 10 is an enlarged side view of one of the top jet devices.

Fig. 11 is a bottom view of the jet device shown in Fig. 10.

Fig. 12 is an enlarged longitudinal sectional view of one of the bottom jet devices.

Fig. 13 is a top view of the jet device shown in Fig. 12.

Fig. 14 is a transverse sectional view taken along the line 14—14 of Fig. 10.

Fig. 15 is a transverse sectional view taken along the line 15—15 of Fig. 10.

In order to clearly illustrate the invention I have shown a dish washing machine of the type wherein the main casing is provided with two openings adapted respectively for the supply and discharge of the dishes to be washed. The dishes may be placed in racks and moved continuously or otherwise through the casing and while in the casing they may be subjected to the action of washing and rinsing liquids. While the invention is particularly applicable to a machine of this type it will be understood that as to most of its features it is not so limited.

The machine is provided with a casing 1 and a tank 2, both of which are supported on a main framework 3 having feet 4, 4. The casing 1 is shown as being of generally rectangular cross section; and it is provided at the left end with a supply opening 5 and at the right end with a discharge opening 6.

The tank 2 is adapted for containing the main supply of washing liquid. Preferably this tank is immediately below a portion of the casing 1, and as a matter of structural convenience the said casing and tank may be formed as a single unit as shown. The tank preferably extends throughout the entire length of the casing, but is preferably considerably narrower so as to leave a space at the front. Liquid can be supplied

to the tank through a pipe connection at 7 and excess liquid in the tank may be discharged through an overflow pipe 8. In order that the casing may be emptied when desired there is provided a drain pipe 9 controlled by a valve 10.

Carried by the framework 3 in the space below the casing 1 and at the front of the tank 2 is a platform 11, which serves to support certain parts to be presently described.

10 Within the casing 1 is a support for the dishes to be washed, and this support may be variously formed without departing from the spirit of my invention. However, I have shown a dish support adapted to receive and guide dish carrying racks through the casing, one such rack being indicated at A in Figs. 1 and 2. If desired a combined dish support and conveyor mechanism may be provided. I have shown a guide and conveyor mechanism which is adapted to engage and support dish racks such as A and to move them through the casing from the supply opening 5 to the discharge opening 6. The combined guide and conveyor mechanism is shown as being constructed similarly to that disclosed in my copending application for Dishwashing machine Serial No. 356,572 filed April 19, 1929.

The guide and conveyor mechanism as shown comprises two main side plates or rails 12, 12 which are connected and held in proper spaced relationship by means of spacing rods 13, 13 extending between them. Near one end of the conveyor, preferably the right end, is a rotatable shaft 14 mounted in suitable bearings carried by the side plates 12, 12. Mounted on the shaft 14 adjacent the respective side plates are chain sprockets 15, 15. At the opposite ends of the mechanism are two other chain sprockets 16, 16 carried by the respective side plates. Two endless conveyor chains 17, 17 extend over the sprockets 15, 15 at the respective sides of the machine. The upper portions of the two chains are supported on rails 18, 18 carried by the side plates, and the lower portions of the chains are supported on rails 19, 19 carried by or formed as parts of the side plates. 45 For operating the conveyor there is provided a speed reducing gear box 20 of any usual or preferred construction supported on the platform 11. Projecting from the box 20 is a shaft 21 with a sprocket wheel 22 thereon. A sprocket wheel 23 is provided on the conveyor shaft 14 and a chain 24 passes over and around the two sprocket wheels 22 and 23. When power is transmitted to the gear box 20 in the manner to be described the conveyor chains 17, 17 are operated to carry 55 the dish racks slowly through the casing.

The combined guide and conveyor mechanism is preferably so supported in the casing 1 that it can be readily removed as an entirety, and to this end the dimensions of the said mechanism are 60 such that it can be readily removed through one of the end openings, preferably the opening 6. As shown there are two brackets 25, 25 projecting inward from the right end wall of the casing, these brackets being grooved to receive the cross 65 rod 13 of the conveyor mechanism. At the opposite end of the machine are inward projecting brackets 26, 26 upon which rests the rod 13 at the corresponding end of the conveyor mechanism. When it is desired to remove the conveyor 70 mechanism it is necessary to disconnect it from the chain 24. This may be done by loosening the sprockets 15, 15 and 23 on the shaft 14 and then withdrawing the shaft longitudinally from the said sprockets. In order that the shaft 14 75 may be thus removed there is provided an open-

ing 27 in the side of the casing, this opening being normally closed by a removable cover 28.

For withdrawing liquid from the tank 2 and delivering it under pressure there is provided a pump 29 preferably of the centrifugal type. The 5 pump is mounted on the platform 11 with its axis extending longitudinally of the machine. An electric motor 30 is directly connected with the pump to drive it. A connection from the pump to the gear box 20 serves to drive the latter. 10

The pump 29 has an intake duct 31 with an intake opening therein and a discharge duct 32 with a discharge opening therein. The tank 2 has an outlet opening 33 and the intake of the pump is connected with this outlet opening, preferably by means of a flange member 34 suitably secured to the side wall of the tank.

Connected with the discharge duct of the pump are suitable jet devices for delivering the washing liquid under pressure against the dishes which 20 are being supported or moved within the casing. Preferably there are two sets of jet devices, one above the position or path of the dishes, and the other below the said position or path. These upper and lower devices must be directly opposed, 25 for the reason that the lower jets, if unopposed, would lift and break some of the lighter dishes. The details as to the positioning and mounting of the jet devices may be varied, but one suitable arrangement is shown in the drawings and this 30 will be now described. Located within the casing and directly connected with the discharge duct of the pump is a T-member 35. To the vertical branch of this T-member is connected a vertical pipe 36 which is connected by means of an 35 elbow 37 with a horizontal manifold 38. To the horizontal branch of the T-member 35 is connected a horizontal manifold 39. Connected with the said manifolds 38 and 39 are jet devices 40, 40 and 41, 41 which extend transversely of the 40 casing and are arranged in pairs. The two jet devices of each pair are oppositely disposed and serve to direct jets of washing liquid respectively downward and upward against the dishes supported or moved upon the aforesaid support 45 within the casing.

Inasmuch as the liquid is delivered from the jet devices under high pressure a considerable amount of splash or spray is formed as the result of impact of the jets against the dishes and 50 against the dish racks and particularly as the result of the impact of the oppositely directed jets against each other. In order to avoid an excessive length of casing the oppositely disposed jet devices must be relatively near the supply opening 5 and in order to reduce to a minimum the discharge of splash or spray through this supply opening I provide means adapted to form a curtain of liquid moving continuously in one direction across the path of the dishes between the 60 supply end of the casing and the aforesaid opposed jet devices. The means for forming this liquid curtain may be variously constructed, but I prefer to provide an additional device 42 somewhat similar to the before-mentioned jet devices 40, 40, this additional device being carried by the same manifold 38. It will be observed that the device 42 is entirely out of register with any lower jet device and is thus adapted to produce a curtain of liquid moving continuously in 65 the downward direction.

Inasmuch as the device 42 delivers liquid under considerable pressure, the said liquid serves not only as a curtain to catch and absorb the heavy splash formed by the aforesaid opposed spray 75

devices 40, 40 and 41, 41, but it also serves in and of itself as an effective means for removing from the dishes the larger and heavier particles of food which may adhere to them. It will be obvious that the action of this preliminary curtain or spray device on the dishes is very effective and advantageous as it prevents the aforesaid larger particles of food from being caught between the main opposed jets where they might be held by the balancing action of the said jets and possibly eventually redeposited upon the dishes.

The curtain produced by the device 42 serves as already stated to absorb the larger portion of the splash caused by the opposed jet devices 40, 40 and 41, 41. The said device 42 does not of itself cause any large amount of splash by reason of the fact that all of the liquid is moving in one direction and is unopposed by liquid moving in the opposite direction. However, notwithstanding this fact, the device 42 does cause some splash and in order to prevent this from passing out through the supply opening 5 I provide a very effective combination of splash walls and flexible curtains between the said supply opening 5 and the said device 42. As shown there are two transverse splash walls 43 and 44. Each of these walls extends along the two side walls of the casing and across the top thereof as clearly indicated in Figs. 3, 4 and 5. Carried by the said splash walls 43 and 44 are hooks 45, 45 and 46, 46. The hooks 45, 45 are adapted to receive a transverse rod at the top of a flexible curtain 47 and the hooks 46, 46 are adapted to receive a transverse rod at the top of a flexible curtain 48. It will be obvious that the said curtains 47 and 48 can be readily removed for inspection, cleaning or replacement, and that they serve when in place to effectively prevent any splash from passing out through the opening 5. When dishes are inserted the said curtains 47 and 48 are momentarily lifted by the dishes, but even then there can be but a small amount of splash at the opening 5 as the major splash from the jet devices 40, 40 and 41, 41 is stopped by the liquid curtain produced by the device 42 as already explained.

After the dishes have passed beyond the zone of action of the jet devices 40, 40 and 41, 41 they enter a rinsing zone where they are acted upon by upward and downward moving jets or sprays of rinsing liquid delivered by jet or spray devices 49, 49 and 50, 50. These spray devices are connected by means of suitable piping with a valve 51, hot water being delivered to the said valve through a pipe 52 adapted to be connected with a suitable independent source of hot water. The valve 51 is normally closed but is adapted to be opened by means of a lever 53 which normally projects into the path of the dish racks. When a dish rack by its movement engages the said lever 53 the lever opens the valve 51 and permits the hot rinsing water to flow to the rinsing nozzles 49, 49 and 50, 50. Preferably splash walls 54 and 55 are provided at both ends of the rinsing zone and with them are associated flexible curtains 56 and 57. These splash walls and flexible curtains are or may be similar to the splash walls and curtains already described.

In using the machine the dishes to be washed are placed in racks such as A and these racks are introduced successively through the supply opening 5 so as to be supported by the conveyor chains 17, 17. The dish racks are slowly moved by the conveyor from left to right through the casing, the dishes therein being first engaged by the downward moving curtain or series of jets from

the device 42 and being thereafter engaged by the opposed jets delivered by the jet devices 40, 40 and 41, 41. When the dish racks emerge from the washing zone to the rinsing zone they engage the lever 53 to open the valve 51 as before described, thus causing rinsing water to be directed against the dishes through the spray devices 49, 49 and 50, 50. Finally the dish racks emerge through the discharge opening 6.

The main casing 1 is preferably provided at 10 one side, ordinarily the front side, with an inspection opening normally closed by a door 58 which is movable vertically. Heretofore difficulties have been experienced with an inspection door such as the door 58, in that liquid from the interior would escape around the edges of the door, thus causing objectionable moisture on the outside of the machine and on the floor beneath. When the door is opened, even with the jet or spray devices inactive, a considerable amount of liquid may drip from the lower edge of the door and may find its way along the outside of the casing onto the floor. In accordance with the present invention I provide a guide or frame for the door which is so constructed as to collect all liquid in the vicinity of the door and direct it back into the interior of the casing.

For supporting and guiding the door 58 I provide a frame which at least partly surrounds the inspection opening. As shown the frame comprises an outer member 59 which engages the outer surface of the corresponding side wall of the casing. The said frame member 59 engages the door 58 at its outer surface and guides it for vertical sliding movement. This frame member 59 is preferably a casting, though as to this I do not limit myself. As shown the frame member 59 is provided across the bottom portion thereof with a flange 60 which is spaced from the door 58 and which will collect liquid and prevent it from flowing downward along the outer surface of the frame.

I preferably provide a second or inner frame member 61 which surrounds the inspection opening but is located at the inner surface of the side wall as shown in Fig. 7. The two frame members 59 and 61 are held together by bolts 62 which extend through suitable openings in the front wall of the casing 1. It will be observed that the frame member 61 is provided with a flange 63 which is so positioned and shaped as to engage the inner surface of the door 58, the said door being thus guided between the two frame members. The door frame, whether formed of two separate members 59 and 61 or otherwise formed, is provided in its bottom portion with a transverse slot 64 into which the lower portion of the door projects when in closed position. One or more openings 65 are provided which permit liquid in the slot 64 to be drained back into the interior of the casing.

It will be obvious that with the construction shown any moisture finding its way around the edges of the door or dripping from the door when the door is in open position will be guided into the slot 64, this action being facilitated by the flange 60 already mentioned. Liquid entering the slot 64 will drain through the opening 65 into the interior of the casing.

For collecting and retaining scraps of food and other solid matter I provide a series of scrap trays 66, 66 across the top of the tank 2. These scrap trays are freely removable, removal being most conveniently effected by the supply end of the machine. It will be understood that the

several scrap trays can be moved longitudinally so as to come within convenient reach of the operator at the supply opening 5.

In order to prevent excessive turbulence within the tank 2 I preferably provide a suction guard 67 for the pump intake. This guard is box-like in form and extends transversely of the tank. One end of the guard communicates with the pump and the guard is closed at its opposite end and also at the top and is furthermore substantially closed at the sides. The bottom is open except for a screen 68 and this screen may extend part way up the sides as shown in the drawings. It will be observed that even though the scrap trays 66 were omitted the guard 67 and the screen 68 would effectively prevent solid matter from entering the pump. The guard 67 not only prevents solid matter from entering the pump but it reduces turbulence in the tank and therefore enables the pump to operate more efficiently. Furthermore even though the liquid in the tank 2 should be seriously depleted the pump will continue to operate as the guard 67 prevents any air from entering the pump even though the level of the liquid in the tank be reduced considerably below the top of the tank outlet opening.

The main jet or spray devices 40, 40, 41, 41 and 42 may be varied in construction, but in the drawings, particularly Figs. 10 to 13, I have shown one form of construction which is highly advantageous. Each of these devices is or may be substantially the same in construction, and therefore a description of one of them will suffice for all.

Each jet device comprises a duct 69, preferably a casting, which is open at one end to receive liquid from the corresponding manifold 38 or 39. Preferably the manifold is provided with a socket into which fits a cylindrical portion 70 on the duct, this cylindrical portion being clamped and held in place by means of a clamping ring 71 provided with a clamping screw 72. Adjacent the cylindrical portion 70 is a pin or stud 70^a adapted to enter a notch in the clamping ring to determine the proper location of the jet device. The duct 69 is closed at the end opposite the end which communicates with the manifold and is provided along one side with an open slot 73. Covering the slot 73 is a removable plate 74 having apertures or slots 75, 75 therein for delivering jets or sprays of liquid.

In order that the direction of flow through the apertures 75, 75 may be substantially perpendicular to the axis of the duct, I provide means in the duct for preventing, or at least restricting, the longitudinal flow of the liquid along that side of the duct which is adjacent the slot 73 and the apertured plate 74. Preferably the means for restricting the longitudinal flow comprises cross elements or bars 76 formed integrally with the duct 69. Referring by way of example to Fig. 12 it will be apparent that these cross elements or bars 76 restrict the longitudinal flow to the lower portion of the duct, thus making it possible for the liquid to flow upward from the said lower portion to the apertures 75, 75 in the plate.

I have shown the slot 73 as being formed in a flat surface 77 on the duct 69, which surface is parallel with the axis of the cylindrical portion 70 of the duct. The plate 74 is provided with a similar flat surface, thus providing a tight joint between the duct and the plate. Preferably the plate 74 is provided with hollow bosses 78, 78

registering with the respective cross bars 76, 76. Screws 79, 79 extend through the bosses 78, 78 and into the cross bars 76, 76, thus firmly holding the plate 74 in place. The said plate 74 is preferably transversely curved with its convex surface outward. The apertures 75, 75 in the plate may vary as to size, shape and spacing, so as to provide the required types and forms of jets or sprays, but I have shown rectangular apertures diagonally positioned.

It will be apparent that with the construction which I have shown the entire jet device can be easily removed by loosening the clamping ring 71. After removal the plate 74 can be readily detached to provide access to the interior of the device. It is then possible to easily clean the interior of the duct 69 and also to clean both sides of the plate 74. Should the plate 74 become worn or broken it can be easily replaced; or the said plate can be replaced by another plate having apertures of a different character.

What I claim is:

1. A washing machine for dishes or similar articles, comprising in combination a main casing having supply and discharge openings at opposite ends thereof, means in the casing for guiding the articles to be washed through the casing from the supply opening to the discharge opening, a pair of similar oppositely disposed upper and lower jet devices in the casing respectively above and below the path of the articles being guided through the casing for directing jets of washing liquid respectively downward and upward against the said articles, and means for projecting a curtain of liquid moving continuously in one direction across the path of the articles between the supply end of the casing and the said opposed spray devices.

2. A washing machine for dishes or similar articles, comprising in combination a main casing having supply and discharge openings at opposite ends thereof, means in the casing for guiding the articles to be washed through the casing from the supply opening to the discharge opening, a pair of similar oppositely disposed upper and lower jet devices in the casing respectively above and below the path of the articles being guided through the casing for directing jets of washing liquid respectively downward and upward against the said articles, and an additional upper jet device above the said path for directing jets of washing liquid downward against the articles, the last said jet device being out of register with any lower jet device and being positioned between the supply end of the casing and the first said jet devices.

3. A washing machine for dishes or similar articles, comprising in combination a main casing having supply and discharge openings at opposite ends thereof, means in the casing for guiding the articles to be washed through the casing from the supply opening to the discharge opening, a pair of similar oppositely disposed upper and lower jet devices in the casing respectively above and below the path of the articles being guided through the casing for directing jets of washing liquid respectively downward and upward against the said articles, means for projecting a curtain of liquid moving continuously in one direction across the path of the articles between the supply end of the casing and the said opposed spray devices, a plurality of transverse splash walls within the casing between the said curtain projecting means and the supply end of the casing, each of the said walls extending along the two side walls of the casing and across the top, and a plurality of

transverse flexible curtains closely associated with casing, a transverse splash wall within the casing extending along the two side walls and across the top, a transverse flexible curtain extending between the side portions of the splash walls and having at the top a supporting rod with projecting ends, and hooks on the splash walls for engaging the projecting ends of the rod to detachably support the curtain.

4. In a washing machine for dishes or similar articles, the combination of a main casing having supply and discharge openings at opposite ends thereof, means in the casing for guiding the articles to be washed through the casing from the supply opening to the discharge opening, jet devices in the casing for directing jets of washing liquids against articles being guided through the

GEORGE WEBB.

10
